UNITED STATES PATENT OFFICE.

FRANK J. REYNOLDS, OF ROCKVILLE CENTER, LONG ISLAND, NEW YORK.

CARD-HOLDING DEVICE.

Application filed July 14, 1922. Serial No. 574,914.

To all whom it may concern:

Be it known that I, FRANK J. REYNOLDS, a citizen of the United States, a resident of Rockville Center, Long Island, in the county 5 of Nassau and State of New York, have invented a certain new and useful Card-Holding Device, of which the following is a specification.

This invention relates to a card holding 10 device in combination with a shipping case.

This invention relates also to a card holding device and more particularly a device adapted to hold cards indicating the contents of a shipping box containing textile 15 goods, said device being attached to the shipping box in a convenient manner.

While the invention may exist in various embodiments, the following description is intended to cover a preferred embodiment of 20 the invention which has been found very convenient and advantageous in practical use.

The said preferred embodiment is illustrated in the accompanying drawings which 25 form part of this specification and in said drawings,—

Figure 1 represents a shipping box designed to contain textile goods, the card holding device being shown attached to said 30 shipping box to provide a combined structure.

Figure 2 shows a card inserted in the card holding device, this figure being in the same position as the card holding device in 35 Figure 1 but the view being from the inside of the box outwardly.

Figure 3 is a section of Figure 2 on line 3—3.

Figure 4 is a modification of the card 40 holding device.

Figure 5 is a section thereof on line 5—5 of Figure 5.

In the drawings a shipping box or packing case 1 is shown and there is attached thereto 45 a card holding device denoted generally by 2. This device is preferably and advantageously attached to the shipping case at the upper edge thereof underneath and against the lower side of a board 3 of the shipping case which in the usual form of construction is nailed or screwed to the main body of the case and stands out from the outside surface thereof. The card holding device is attached by means of hinges 4 as 50 shown, these hinges lying flat against the lower rear end of the card holding device

and against the side of the board 3, in such a manner that the device 2 may be lifted up and turned through 180° into an upright position as shown by the dotted lines in 60 Figure 1 represented by numeral 5. When in the latter position the card denoted by the numeral 6 will appear exposed to view so that the contents of the card may be inspected and read. A suitable fastening device 7 may be provided at the lower end 8 of 65 the card holding device in order to hold it against the side of the shipping case. Any suitable device may be used for this purpose and it will advantageously consist of a 70 structure not easily broken during transit.

The card holding device 2 consists of a board or plate 9 which has attached thereto at three sides frames 10, 11, and 12, these frames being provided with recesses between 75 the board 9 and the overhanging portions of the frames so that a card may be slipped in between the frames and the board as clearly shown in Figure 2. The device 2 may be of wood, iron, or other suitable material. 80

In the modification shown in Figure 4 a metal frame denoted generally by 13 surrounds the board 9' at three sides thereof and also has a groove or slot between the frame and the board 9' to admit a card. 85 This metal frame may extend over the back of the board 9' as shown in Figure 5 and denoted generally by the numeral 14.

The view shown in Figure 2 is, of course, the reverse of the view which will present 90 itself when the card holding device is swung up into position 5, that is, it is upside down with respect to position 5.

In this manner there is provided a card holding device which is easily accessible and 95 yet out of the way so that it will not be damaged during transit by coming into engagement with other shipping cases or boxes. Advantage is taken of the recesses which are customarily found in the usual shipping 100 cases to place therein the card holding device. This may be mounted in any position within said recesses and may be advantageously situated in one of the corners thereof. It may, however, be positioned 105 and fastened underneath any overhanging portion of any shipping case or it may be fastened below a specially provided ledge or overhanging board where shipping cases are built in a peculiar or unusual manner. 110 The card holding device is quite simple in construction and securely protects the con-

tained card from the weather and from damage due to abrasions or accidental tearing. The card is always accessible and therefore the invention obviates the difficulty of having to open the shipping case and search for the card among the contents thereof. If desired the locking or holding means may be made in the form of a lock which only the consignee can open with a key or it may comprise any other locking device which will prevent access to the card by unauthorized persons.

As many apparently widely different embodiments of this invention may be made without departing from the spirit thereof, it is to be understood that I do not limit myself to the details of the above embodiment

except as may be indicated by the appended claim which defines the invention.

I claim:

The combination of a shipping case constructed with reinforcing boards along the edges to provide a recess having a reentrant angle in the side of the case, and a base plate hinged at its lower rear side to one of the said boards adjacent said angle so as to occupy a portion of the recess, said base plate carrying a card with its face toward the shipping case and in inverted position.

In testimony that I claim the foregoing, I have hereunto set my hand this 11th day of July, 1922.

FRANK J. REYNOLDS.
